UNITED STATES PATENT OFFICE

FREDERICK S. HAAS AND CLEMENT BOOTH, OF CINCINNATI, OHIO, ASSIGNEES TO CINCINNATI GRINDERS INCORPORATED, OF CINCINNATI, OHIO, A CORPORATION OF OHIO

GRINDING MACHINERY

Application filed September 27, 1929. Serial No. 395,703.

This invention relates to improvements in grinding machinery and has particular reference to mechanism for maintaining the operative surface of the grinding wheel in proper condition.

One of the principal objects and advantages of the present invention is the provision of a mechanism particularly adapted for the semi-automatic truing of the operative surface of a grinding or abrasive wheel or like rotating member.

A further object of the invention is the provision of a mechanism capable of manual or other control which will enable a relatively unskilled operator to successfully produce a smooth properly trued surface on an abrasive wheel without the formation of grooves or ridges or the like and without liability of injury to the diamond or other truing tool employed.

A further object of the invention is the provision of an improved manually controllable truing mechanism for grinding wheels or the like which will relieve the operator of the laborious hand actuation thereof and which will be capable of shifting through full or limited strokes as desired and large varying rates of speed according to the work being performed at an individual moment.

An additional object of the present invention is the provision of an improved automatic mechanism for attaining proper relative feeding movement of the tool with respect to the surface being operated upon at each traverse thereof whereby uniformity of truing and liability of deep setting causing either gauging of the wheel or damage to the diamond of truing tool to be prevented.

Other objects and advantages of the present invention should be apparent by reference to the following specification considered in conjunction with the appended drawings forming a part thereof and it will be understood that we may make any modifications in the specific structural details hereinafter disclosed within the scope of the appended claims without departing from or exceeding the spirit of the invention.

Figure 1 is a side elevation of a grinding machine equipped with our improvements.

Figure 2 is a top plan view thereof.

Figure 3 is a transverse sectional view taken on the line 3—3 of Figure 2.

Figure 4 is a vertical section as on the line 4—4 of Figure 1.

Figure 5 is a section on line 5—5 of Figure 4.

Figure 6 is a section through the actuating lever and parts affected thereby as on line 6—6 of Figure 1.

Figure 7 is a vertical section on the line 7—7 of Figures 2 and 3.

Figure 8 is a vertical section on line 8—8 of Figure 7.

Figure 9 is a horizontal section through the feed piston on line 9—9 of Figure 8, and

Figure 10 is a diagrammatic view of the hydraulic control circuit and parts actuatable thereby.

In the drawings in which similar characters of reference are employed to denote corresponding views the numeral 15 designates the bed of a centerless grinding machine having a head 16 in which is journaled the grinding wheel 17 actuatable in a clockwise direction for operation on the work piece 18 supported by work rest 19.

The present invention has been shown as applied to and utilized in conjunction with the grinding wheel member of a machine of this type since due to the requirements as to accuracy of production of work upon centerless grinders the truing of the grinding wheel is of maximum importance.

Suitably supported by the bed 15 is a bracket 20 bearing a trunnion 21 for the supplemental truing fixture bracket 22 secured in angularly adjustable position as by bolt 23. This bracket supports the guide block 24 having the dove-tailed ways 25 on which is slidably mounted the tubular housing 26 for the truing tool.

Member 24 has a projection 27 forming a head at one end of and supporting cylinder 28 containing the oscillatable piston 29, a plug 30 forming a closure for the opposite end of the cylinder.

Coupled with opposite ends of this cylinder are conduits 31 and 32 for selectively introducing actuation fluid to and contacting

same from opposite ends of the cylinder to effect desired reciprocation of piston 29. This piston is coupled by a rod 33 with slide 26 for actuation of the slide.

5 Conduits 31 and 32 terminate at the valve housing 34 containing the suitably ported bushing 35 and slide valve 36. An inlet 37 extends to the housing and is in communication with the interior of bushing 35, suitable 10 actuating fluid being supplied thereto from reservoir 38 as by intermediately disposed pump 39. Depending from the housing is an outlet or discharge conduit 40 adapted to return fluid from the system to the reservoir.

15 The valve member 36 has a spool portion 41 engaged by arm 42 on rock shaft 43 journaled in the valve, and having pivotally secured to its outer end the actuating handle or lever 45. A spring 46 tends to normally urge valve to 20 a left hand position as viewed in Figure 5, in which the porting then serves to couple the left hand end of the piston with the discharge port and the right hand end with the pressure so that the actuating pressure will 25 hold the piston and thus the truing slide unit toward the rear of the machine in a normal, inoperative position.

When it is desired to effect a truing operation handle 45 is shifted to move the valve to 30 the right causing the connections to be reversed so that the actuating fluid flows from the valve through conduit 32 to the outer end of the piston while the inner end of the piston is coupled through conduit 31 and the valve 35 through a discharge passage 47 in the housing. This passage includes a seat 48 for a chuck valve 49. This valve is intermediately located on the stem 50 having its terminal portions journaled in the packing nuts 40 51—52 to prevent leakage of the actuating fluid. The stem being supported for both sliding and retarding movement. Nut 51 is carried by a sleeve nut 53 having a cylindrical portion 54 supporting and guiding the 45 spring 55. A bushing 56 is slidably but non-rotatably mounted in the aperture 57 interorily of the member 53 and is urged against shoulder 58 by action of the opposite end of spring 55 thereagainst. Stem 50 has a 50 threaded portion 59 engaged with the bushing whereby the stem may be adjusted relative the bushing, the engagement of the bushing and shoulder determining the inward limit of movement of the valve under 55 influence of spring 54. These parts are shown in section in Figure 4 from which it will be noted that rotation of the valve stem by the knurled operating head 60 will serve to adjust the position of valve 49 with respect to the seat 48 and thus the amount of choking of the return passage. This choking or throttling will control the rate of movement of the piston and thus of the truing tool in either direction.

60 By reference to Figures 4 and 6 it will be

noted that the stem 50 projects rearwardly from the housing and has its terminus resting against the intermediately pivoted lever member 61 whereas the opposite end is engaged by pin 62 and projected by engagement of the inner face of yoke 63 forming the pivotal connection between shaft 44 and operating handle or lever 45.

Consequently, when lever 45 is pushed inwardly or in a direction toward the machine 75 motion will be transmitted thereby through pin 62 to rock lever 61. This in turn will press valve stem 50 toward the front sliding bushing 56 forwardly against the pressure of spring 55 thus releasing the choking in the discharge line. This results in a rapid traverse of the piston and associate tool and it will be understood that the width of yoke 63 is such that the lever may receive the necessary valve effecting oscillation while still 85 holding the pin depressed.

Consequently, continuous or in turn rapid 90 traverse may be effected and in either direction as the desired single lever controlling the directional movement of the truing tool slide and also the rate at which the operation is effected.

In order that the operation of the entire machine may be as near entirely automatic as possible means are provided not only for power reciprocation of the truing slide but also for an automatic inward feeding of the tool a predetermined amount for each cycle of reciprocation thereof. The truing tool mechanism proper is illustrated in section in Figure 7 and includes the tool holder or plunger 64 bearing at its inner end the truing tool or diamond 65. This member is keyed as at 66 against rotation relative the support 26 therefore and has a threaded socket as at 67 to receive adjusting screw 68. Screw 68 has a flange 69 bearing against the under side of cap 70 carried by the outer portion of the casing 26 and on its outer projecting end bears a hand wheel 71 for rotative adjustment of the screw. This hand wheel has a hub 72 bearing against a cap 73 on the outer end of the housing forming the remainder of the swivel movement of the screw and preventing longitudinal movement. Cap 70 100 has a projecting sleeve portion 74 circumscribing the outer portion of the screw and forming a bearing for the oscillatable rack member 75. This member as is clearly illustrated in Figure 8 supports a pivot pin 76 105 intermediately engaging pawl 77 having at one end the teeth 78 for engagement with ratchet 79 when the gear 75 and pawl are rocked in a clockwise direction the angle of the tooth and the engaging teeth of the ratchet being such that the ratchet will ride idly in a reverse direction and a second pin 80 serves as a support for spring 81 normally urging the pawl into engagement with the ratchet. An adjustable supply screw 83 is 110

carried by the member 26 and projects into the path of movement into the rearward or spring engaged portion for engagement of these parts upon reverse oscillation of the 5 pawl which tends to cam the pawl inward out of engagement with the ratchet and the point of release. Thus re-engagement of the pawl and ratchet on reverse movement of the pawl may be determined and thus the 10 amount of shift of the ratchet may be determined by adjustment of the screw 83. The ratchet in question is keyed on the intermediate portion of the screw so that shifting of the ratchet will correspondingly advance 15 the screw therewith imparting a slow inward feeding movement to the truing diamond.

Inasmuch as in its reverse position the pawl is held back away from the ratchet the screw may additionally be given manual 20 adjustment in either direction as desired.

For effecting the automatic adjustment a cylinder chamber 85 is formed in the member 26 receiving and guiding piston 86 having a rack 87 meshing with the teeth on the 25 pressure of the slideable pawl carrier 77 so that on retraction of the piston an oscillatory movement will be imparted to the pawl. The degree of feeding movement of each oscillation may further be controlled by adjusting the end stop members 88 and 89 which have a suitable screw or threaded mounting for this purpose as shown in Figures 8 and 9. The less the movement allowed the piston in a left hand direction the less the feeding 30 movement which will be given to the screw upon each individual actuation of the piston. It will be noted by reference to Figures 1 and 10 that the leads or conduits 90 and 91 to the cylinder 85 are coupled respectively with the leads 31 and 32 with the cylinder 28. Consequently, the piston 86 will be moved to the right as viewed in Figure 8 when the piston 29 is moved to the left as viewed in Figure 3 the path being retracted 35 or shifted toward the rear of the machine which is their normal position. When the valve is shifted to cause a movement of the truing tool transversely of the wheel, piston 86 is also actuated to cause an increment of inward feeding movement of the tool from the position last occupied in traversing the wheel. As the movement of the piston is relatively slight, the inward feeding movement is effected before the tool itself moves 40 within the lateral point grinding wheel so same is set to true off the surface of the wheel so that the wheel is worn greater at the front than at the rear side. The tool may be taught to traverse the wheel until 45 the stock and control 35 is pressed inward causing a rapid reverse or return movement of the tool on account of relieving for opening of the throttle valve 49.

This also carries the pawl back in a position to take another feed bite on the screw

ratchet. When the machine is reversed the tool is again moved inward and adjusted the predetermined increment and is then caused to traverse the grinding wheel surface at the rate determined by the lever 35.

From the foregoing description the operation of the present improved invention should be readily understood and it would seem the operator is relieved of the necessity of slow hand traversing of the diamond and the additional necessity of manual determination of amount which the diamond should be fed in each instance and the necessity of utilizing both hands for effecting the prescribed and desired truing. Instead of by manipulation of one lever and utilizing but one hand the diamond truing tool may be caused to traverse the wheel forward taking a rough cut and rearwardly taking a finished cut smoothing off the surface if desired at the same rate or its rate of progress may at any time be accelerated as desired.

In addition, the truing tool is automatically fed in once for each cycle of back and forth movement of the tool. Irrespective of the extent of such movement and in any event, is given but one feeding movement for each reciprocation. It will of course be understood that by a jiggling of the lever the piston could be relatively shifted to produce several operative actuations of the feed control system without bringing the tool into engagement with and transversely of the grinding wheel surface and likewise that such desired additional adjustment could be procured as preferred by a manual adjustment of the truing tool by rotation of handle 71 and thus associate screw without actuation of the hydraulic mechanism.

We claim:

1. A mechanism of the nature described including a support, a slide movable transversely of the support, a tool holder movable transversely of the slide, a piston for actuation of the slide, a second piston for actuation of the tool holder, respective cylinders operatively supporting the pistons, a source of hydraulic power, and means for simultaneously coupling the source of power with one end or the other of each of the cylinders for simultaneous actuation of the feed and traverse controlling pistons whereby the tool is incrementally fed toward a grinding wheel at the initiation of the movement of the slide.

2. In a truing mechanism of the class described for operation on an abrasive wheel, the combination of a support, a slide transversely movable on the support, a holder carried by the slide, hydraulically actuatable means for effecting a traversing movement of the slide, hydraulically actuatable means for effecting a continuous incremental feeding of the holder with respect to the slide, an hydraulic circuit for the hydraulically actuatable means including a start and stop

valve, a throttle mechanism for normally retarding the rate of actuation of the parts including a valve, and a single control member for determining the effective position of both of said valves.

3. In a truing mechanism of the character described for operation on an abrasive wheel, the combination of a support, a slide traversely movable on the support, a holder carried by the slide, hydraulically actuatable means for effecting a traversing movement of the slide, hydraulically actuatable means for effecting a continuous incremental feeding of the holder with respect to the slide, an hydraulic circuit for the hydraulically actuatable means including a start and stop valve, a throttle mechanism for normally retarding the rate of actuation of the parts including a valve, and a single control member actuatable in one direction to determine the direction of movement of the traversing and feeding mechanisms and in a different direction to effect the rate of actuation thereof.

4. In a truing mechanism of the character described for operation on the active face of an abrasive wheel, the combination with a support, of a slide movable thereon, a truing tool carried by and movable relative to the slide toward the abrasive wheel, hydraulically actuatable means for traversing the slide, additional hydraulic means for advancing the tool relative to the slide at incremental rates, and means controlling the actuation of the parts by the hydraulic means for movement at feed and quick traverse rates.

5. In the machine tool organization the combination of a bed, a grinding wheel rotatably supported thereby, a bracket adjacent the grinding wheel and having a guide way thereon, a slide supported by the bracket and movable longitudinally of the guide way, a truing tool holder on the slide and movable transversely thereof, an hydraulically actuatable piston operatively connected with the slide for shifting same, an hydraulically actuatable piston for moving the truing tool holder, a hydraulic pressure source, conduits therefor extending to the pistons, a single valve controlling the flow of the pressure source through the conduits, and a control member mounted on the bed for actuating the valve.

6. In the machine tool organization the combination of a bed, a grinding wheel rotatably supported thereby, a bracket adjacent the grinding wheel and having a guide way thereon, a slide supported by the bracket and movable longitudinally of the guide way, a truing tool holder on the slide and movable transversely thereof, an hydraulically actuatable piston operatively connected with the slide for shifting same, an hydraulically actuatable piston for moving the truing tool holder, a hydraulic pressure source, conduits therefor and extending to the pistons, a single

valve controlling the flow of the pressure source through the conduits, a control member mounted on the bed for actuating the valve, a throttle mechanism including a second valve for controlling the rate of flow of the pressure source, and means connected with the control member for actuating the throttle mechanism valve whereby a common control for the direction and throttle valves is provided.

7. In the machine tool organization the combination of a bed, a grinding wheel rotatably supported thereby, a bracket adjacent the grinding wheel and having a guide way thereon, a slide supported by the bracket and movable longitudinally of the guide way, a truing tool holder on the slide and movable transversely thereof, an hydraulically actuatable piston operatively connected with the slide for shifting same, an hydraulically actuatable piston for moving the truing tool holder, a hydraulic pressure source, conduits therefor and extending to the pistons, a single valve controlling the flow of the pressure source through the conduits, a control member mounted on the bed for actuating the valve, a throttle mechanism including a second valve for controlling the rate of flow of the pressure source, means connected with the control member for actuating the throttle mechanism valve whereby a common control for the direction and throttle valves is provided, and a casing enclosing the valves and having pivoted thereto the control member.

8. In a device of the class described the combination of a rotatable grinding wheel, a support adjacent the active face of the grinding wheel, a slide on the support and movable traversely thereof, a truing tool holder on the slide and movable transversely of the slide, hydraulically actuatable pistons for actuating the slide and truing tool holder, a hydraulic medium under pressure, a pair of conduits for the medium, said conduits being branched at one end thereof and respectfully connected with the slide and truing tool holder pistons whereby they are simultaneously actuated, and a single valve for directing the hydraulic source to either conduit for actuating the pistons simultaneously in either direction.

9. In a device of the class described the combination of a rotatable grinding wheel, a support adjacent the active face of the grinding wheel, a slide on the support and movable traversely thereof, a truing tool holder on the slide and movable transversely of the slide, hydraulically actuatable pistons for actuating the slide and truing tool holder, a hydraulic medium under pressure, a pair of conduits for the medium, said conduits being branched at one end thereof and respectfully connected with the slide and truing tool holder pistons whereby they are

- simultaneously actuated, a single valve for directing the hydraulic source to either conduit for actuating the pistons simultaneously in either direction, a second valve in one of the conduits for varying the rate of flow of the hydraulic medium therethrough and consequently varying the rate of movement of the slide or truing tool holder, and a lever common to both valves and shiftable in different directions for controlling the said valves.
10. In a device of the class described the combination of a rotatable grinding wheel, a support adjacent the active face of the grinding wheel, a slide on the support and movable transversely thereof, a truing tool holder on the slide and movable transversely of the slide, hydraulically actuatable pistons for actuating the slide and truing tool holder, a hydraulic medium under pressure, a pair of conduits for the medium, said conduits being branched at one end thereof and respectfully connected with the slide and truing tool holder pistons whereby they are simultaneously actuated, a single valve for directing the hydraulic source to either conduit for actuating the pistons simultaneously in either direction, a second valve in one of the conduits for varying the rate of flow of the hydraulic medium therethrough and consequently varying the rate of movement of the slide or truing tool holder, a lever common to both valves and shiftable in different directions for controlling the said valves, and a bed supporting the grinding wheel, a housing on the front of the bed inclosing the direction and rate control valves and having pivoted thereto the common control lever.
11. In a machine tool organization the combination of a bed, a grinding wheel rotatably mounted thereon, a guideway adjacent the grinding wheel and extending transversely thereof, a slide mounted thereon for movement relative thereto, a truing tool mounted on the slide for movement toward the grinding wheel, hydraulic means for shifting the slide, a screw carried by the slide having an operative coupling with the tool, a reciprocating rack supported by the slide, a segmental gear journaled on the slide and operatively coupled with the rack, a ratchet secured to the screw, and a pawl on the segmental gear for engagement with the rack whereby reciprocations of the rack and oscillations of the gear through the ratchet and pawl incrementally feed the tool toward the grinding wheel for each reciprocation of the rack.
12. In a machine tool organization the combination of a bed, a grinding wheel rotatably mounted thereon, a guideway adjacent the grinding wheel and extending transversely thereof, a slide mounted thereon for movement relative thereto, a truing tool mounted on the slide for movement toward
- the grinding wheel, hydraulic means for shifting the slide, a screw carried by the slide having an operative coupling with the tool, a reciprocating rack supported by the slide, a segmental gear journaled on the slide and operatively coupled with the rack, a ratchet secured to the screw, a pawl on the segmental gear for engagement with the rack whereby reciprocations of the rack and oscillations of the gear through the ratchet and pawl incrementally feed the tool toward the grinding wheel for each reciprocation of the rack.
13. In a machine tool organization the combination of a bed, a grinding wheel rotatably mounted thereon, a guideway adjacent the grinding wheel and extending transversely thereof, a slide mounted thereon for movement relative thereto, a truing tool mounted on the slide for movement toward the grinding wheel, hydraulic means for shifting the slide, a screw carried by the slide having an operative coupling with the tool, a reciprocating rack supported by the slide, a segmental gear journaled on the slide and operatively coupled with the rack, a ratchet secured to the screw, a pawl on the segmental gear for engagement with the rack whereby reciprocations of the rack and oscillations of the gear through the ratchet and pawl incrementally feed the tool toward the grinding wheel for each reciprocation of the rack, and manual means for actuating the screw when the ratchet and pawl are disengaged.
14. In a truing mechanism of the class described the combination with a grinding wheel, of a slide support adjacent the grinding wheel, a slide on the support for translation relative thereto, a truing tool mounted on the slide for movement toward the grinding wheel, an hydraulic piston connected with the slide, an hydraulic piston for feeding the tool toward the grinding wheel, a single source of hydraulic pressure for actuating said pistons, a conduit extending from the single source of pressure to one end of each piston, a valve in said conduit for reversing the flow of the pressure through the conduit, a second valve for controlling the rate of flow of said pressure in said conduit, means for adjustably determining the position of said rate control valve, a lever operable in one direction for axially shifting said reversing valve, and means connecting said lever with the rate control valve whereby operation thereof in an angularly related direction renders the adjusting means inoperative.
15. In a truing mechanism of the class described the combination with a grinding wheel, of a slide support adjacent the grinding wheel, a slide on the support for transla-

tion relative thereto, a truing tool mounted on the slide for movement toward the grinding wheel, an hydraulic piston connected with the slide, an hydraulic piston for feeding the tool toward the grinding wheel, a single source of hydraulic pressure for actuating said pistons, a conduit extending from the single source of pressure to one end of each piston, a valve in said conduit for reversing the flow of the pressure through the conduit, a second valve for controlling the rate of flow of said pressure in said conduit, means for adjustably determining the position of said rate control valve, a lever operable in one direction for axially shifting said reversing valve, and means connecting said lever with the rate control valve whereby operation thereof in an angularly related direction renders the adjusting means inoperative, said connection comprising a plunger abutting on one end with the lever and on the other end with a pivoted beam; and a second plunger abutting on opposite ends with the beam and rate control valve.

25 In testimony whereof we affix our signatures.
